ILLUMINATING DEVICE

Otto Hallbauer, Grantwood, N. J.

Application December 22, 1938, Serial No. 247,185

3 Claims. (Cl. 240—4)

This invention relates to improvements in illuminating devices and has for one of its objects to provide an improved device of simple and practical construction involving the recessing of a source of light within a housing which may be mounted in a support, such as a table top or like structure, and wherein said source of light may be adjusted to an operative position above said support so as to cast the rays of light in a desired direction.

Another object is to mount a lamp housing on a suitable support and provide said housing with a transparent cover which carries said lamp and is adjustable relative to a casing within which said housing is disposed when said casing is raised above said support.

The inventive idea involved is capable of receiving a variety of mechanical expressions, one of which, for purposes of illustration, is shown in the accompanying drawings, wherein:

Figure 1 is a perspective view of a support, such as a table top, showing the illuminating device applied thereto in one position of adjustment.

Figure 2 is a similar view showing the illuminating device elevated above the support.

Figure 3 is a vertical section on the line 3—3 of Fig. 4.

Figure 4 is a longitudinal section on the line 4—4 of Fig. 3.

Figure 5 is a section on the line 5—5 of Fig. 4, and,

Figure 6 is a bottom plan view, partly broken away and shown in section.

The device of the present invention is particularly useful when it is desired to employ a direct beam of light in a room that may otherwise be darkened as, for example, when a television apparatus is in operation and one person within the room wishes to read while others are observing the television screen. The device is adjusted for mounting upon a suitable support such as the top 7 of a table, or the like, and, to so mount said device, said table top is provided with an opening 8 in which the major portion of the device is recessed so as to depend below said top when the device is not elevated thereabove.

The device itself comprises an outer casing 9 opened at its upper and lower ends and provided around three of its sides at said upper end, with a marginal flange 10 which is adapted to rest upon the upper surface of the top 7 to support the casing in position. Disposed within said casing 9 is a lamp housing, generally indicated by the numeral 11, and provided with a hinged arcuate bottom 12 which is adapted to be dropped

or lowered so that access may be had to the incandescent lamp 13 mounted within said housing, said bottom 12 being retained in its normal closed position by a spring latch 14. Arranged within the housing 11 longitudinally thereof and partially encircling the lamp 13 is a shield 15 comprising a substantially semi-circular body having an end plate 16 at one end through which a portion of the socket of the lamp 13 extends, and also having an operating disc 17 at its other end pivotally mounted on one of the end walls of the housing 11. This shield is rotatably adjustable relative to the lamp, by operating the disc 17, so as to direct the rays of light from said lamp in a desired direction when the device is in use and said shield may also act as a reflector. The housing 11 is open at its upper end to which is secured the frame 18 of a cover for said housing, the outer marginal edges of said frame overlapping the edges of the opening 8 in the top 7 and resting upon the upper surface of the latter when the device is in the position as shown in Fig. 1. The operating disc 17 for the shield 15 extends through a slot at one end of the frame 18 so that said disc may be manipulated, to adjust said shield. The frame 18 of the cover forms a central opening which is closed by a transparent element such as a sheet of glass 19 through which the rays of light from the lamp 13 will pass when said lamp is turned on through a suitable switch (not shown). For the purpose of adjusting the housing 11 relative to the casing, the former is pivoted, as at 20, to one wall of said housing.

Means are provided in connection with the device for elevating the casing 9 and housing 11, as a unit, above the top 7 as shown in Fig. 2, and for tilting the housing relative to the casing after said elements have been so elevated. The means for so producing unitary movement of the casing 9 and housing 11 comprises an operating rod or shaft 21 mounted in suitable bearings 22 secured to the underside of the top 7, with one end of said rod projecting beyond one edge of said top and having slidably keyed thereon a spring pressed operating nut 23. The opposed surfaces of the outer bearing and nut are provided with clutch faces 24 which, when engaged with each other, retain the rod 21 in its various positions of adjustment. By disengaging said faces through an outward sliding movement of the nut 23, the latter may be turned to rotate said rod in a desired direction. The inner end of the rod 21 carries a pinion 25 which meshes with a rack 26 formed on the adjacent wall of 55

the casing 9 so that when the rod 21 is turned the casing and the housing contained therein will be raised or lowered relative to the top 7.

The means for tilting the housing 11, with its cover 18, after the said housing and the casing 9 have been elevated, for instance, to the position of Fig. 2, comprises a segmental rack 27 (Fig. 3) secured to one of the end walls of the housing and meshing with a pinion 28 mounted upon a stub shaft 29. This stub shaft 29 projects through the adjacent end wall of the casing 9 beneath the top 7 and has slidably keyed to its outer end the operating nut 30 for turning said pinion 28 in the desired direction. Opposed clutch faces 31 are utilized to maintain the stub shaft 29 in a desired position so that after the housing 11 with its cover 18 have been adjusted as desired the same will remain in position until actuated by an operation of the nut 30. In order that the nut 30 will pass through the top 7 when the casing and housing are elevated, the opening 8 in said top is enlarged as indicated at 32. It is also possible to adjust the inner housing 11 relative to the casing 9 without elevating said elements above the top 7, as indicated by the dot and dash lines in Fig. 3. In this instance, the operator need only reach under the table to grasp the nut 30 to turn the same and thus obtain the tilting movement of the housing and cover. In order that the rear edge of the cover frame 18 adjacent the pivot 20 will clear the table top 7 when said cover is tilted, the wall of the opening 8 in said top adjacent said rear edge of the cover is spaced from the near wall of the casing 9 as indicated at 33.

What is claimed is:

1. The combination with a table top or like

support having an opening therein; of a casing mounted within said opening and depending below said support, means to move said casing vertically through said opening to a projected position above said support, a lamp housing pivoted within said casing and having a top which extends outwardly beyond the upper end of said casing and rests on said support when said casing is in a lowered position, and means to move said housing about its pivot and relative to said 10 casing.

2. The combination with a table top or like support having an opening therein; of a casing mounted within said opening and depending below said support, means to move said casing vertically through said opening to a projected position above said support, a lamp housing pivoted to and normally recessed within said casing and having a hinged bottom and a top the edges of which rest upon said support when said casing 20 is lowered and said housing is recessed therein, and means to move said housing about its pivot and relative to said casing.

3. The combination with a table top or like support having an opening therein; of an open 25 ended casing movably mounted within said opening and having a lower position in which the casing depends entirely below said support, means to move said casing vertically relative to said support, a lamp housing disposed within said 30 casing and pivoted to the upper end thereof, said housing having a hinged bottom through which access may be had to the interior of said housing through the adjacent open end of said casing, and a cover for said housing which also forms 35 a closure for the open upper end of said casing.

OTTO HALLBAUER.
